UNITED STATES PATENT OFFICE.

ERNEST E. HEINTZ, OF DETROIT, MICHIGAN, ASSIGNEE TO TERNSTEDT MANUFACTURING COMPANY, OF DETROIT, MICHIGAN, A CORPORATION OF MICHIGAN.

CURTAIN ROLL.

Application filed August 8, 1921. Serial No. 490,488.

To all whom it may concern:

Be it known that I, ERNEST E. HEINTZ, a citizen of the United States, residing at Detroit, in the county of Wayne and State 5 of Michigan, have invented certain new and useful Improvements in Curtain Rolls, of which the following is a specification.

This invention relates to curtain rolls, and has for its object a curtain roll so 10 designed as to lend itself to large production in an economical and rapid way. The roll is further so designed as to eliminate as far as possible all vibrating parts which are liable to cause annoying rattling when the 15 curtain roll is installed in a closed body automobile. These and other features will be better understood when the detailed description has been given.

In the drawings,—

20 Fig. 1 is an elevation of the long curtain rod before the same has been assembled.

Fig. 2 is an enlarged detail of the end of the curtain rod showing the detent recess and the shoulder.

25 Fig. 3 is a longitudinal section of the major sub-assembly which includes the washers and spring.

Fig. 4 is an enlarged view taken on the line 4—4 of Fig. 3.

30 Figure 5 is an enlarged view taken on the line 5—5 of Fig. 5.

Fig. 6 is an enlarged section taken on the line 6—6 of Fig. 3.

Fig. 7 is an enlarged section taken on the line 7—7 of Fig. 3.

Fig. 8 is an enlarged section taken on the line 8—8 of Fig. 3.

35 Figs. 9 and 9^a are longitudinal sections of the right hand end of the curtain roll showing how the end plate is assembled to the barrel.

Fig. 10 is a view taken on the line 10—10 of Fig. 9.

Fig. 11 is a view showing how the left 45 hand end of the roll is assembled.

Fig. 12 is an enlarged cross section taken on the line 12—12 of Fig. 9^a.

Fig. 13 shows the curtain roll assembled onto the brackets.

50 Fig. 14 is an inside view of the right hand bracket.

Fig. 15 is a section on the line 15—15 of Fig. 14.

The barrel is made of lock-seam tubing 55 and is designated *a*. This lock-seam tubing

is of a character such as shown in Fig. 12 and is made in continuous lengths on rolls or rolls and dies. The tubing is then cut into lengths such as shown in Fig. 9 and notches *b* cut in the ends of the tube by a punching operation. The dies by which the punching operation is achieved can also be provided with points to press the projections *c* and *d* in the barrel to act as stops for a purpose presently to be described.

The rod *e* is placed in a press with suitable dies for upsetting the end to provide the annular shoulder *f*. Between the shoulder and the end a flat *g* is milled on the rod and on the inside of the shoulder is milled a segmental recess to form a pawl 60 recess *h*. The rod is taken in this condition and the felt washer or bearing *i* slipped onto the end. Next the pawl cup sub-assembly or bearing *j* is slipped onto 65 the rod. This is a drawn brass cup with an extending hub *k* that forms a long bearing surface on the rod and also a spring seat. Into this cup *j* is placed a metal washer *m* (Fig. 3). The pawl carrier disk 70 *n* is then inserted. This disk is provided with a sliding gravity pawl or dog *o*. The edge of the cup is then turned over as at 75 *p*, finishing the pawl sub-assembly.

The cloth or fabric sleeve *q* is then slipped 80 over the rod for the purpose of preventing the coils engaging the rod and rattling. Next the torsional spring *r* is slipped onto 85 the end of the rod *e*. The coils at the left hand end of this torsional spring are 90 smaller than the diameter of the rod. Hence to assemble it is found advantageous to place the spring in a tube provided with a shoulder to hold the inner end of the spring. The rod may then be driven down through 95 the smaller spring coils. This jams the spring onto the rod with such a tight press fit that it is equivalent to passing the spring through the rod to tie one end of the spring to the rod. Next the spring and 100 rod are taken in the hand and by turning the spring and at the same time forcing it up over the hub *k* of the pawl assembly, it is possible to screw the right hand end of the spring onto the hub of the pawl assembly 105 to make a press fit. This is equivalent to tying the right hand end of the spring to the pawl assembly by some positive means, such as passing the end of the spring through a hole. The next operation is to 110

slip the small metal washer *s* onto the left hand end of the rod; the felt washer *t* follows, then the small metal washer *u*. Thereupon the left hand end of the rod is put in a suitable press which upsets the keys or stops *v* on the end of the rod. This completes the major sub-assembly which includes, as already stated, the minor sub-assembly, to-wit, the pawl carrier.

Now it has been explained how the barrel is made and notched and punched. The barrel is now taken and the major sub-assembly placed in the right hand end of the barrel. Any suitable press can now be used to force the rod down into the barrel. The pawl carrier assembly will strike the projections or points *d* and will go no farther. The rod will continue until the felt washer *i* strikes the pawl cup. This, when compressed, will stop further entry of the rod into the barrel. Of course, a light pressure ram is used for this purpose which will not force the parts beyond the stops.

Next the end plate *w* is placed over the lugs *x* protruding from the notched end of the barrel. This is placed in a suitable light press which by a couple of operations with two separate dies folds over the lugs to lock the end plates in place. This now prevents the sub-assembly from sliding out of the end of the barrel. The barrel is now placed over an arbor which seats the inner end of the rod and acts as an anvil. Thereupon, a press and ram is used to drive the bracket shown in Figs. 14 and 15 down upon the flattened end *g* of the rod. The opening *g* in the casting that forms the bracket is of slightly less size than the flattened end of the rod and consequently requires a press operation to force this bracket down onto the end of the rod. When pressed in place in this manner the rod and bracket are locked together as a unit and will not come loose. This bracket, when locked in place, holds the rod from pressing into the barrel, due to the compressibility of the felt washer. The rod must be held in a prescribed position with respect to the barrel or the pawl will not line up with the pawl recess.

The next operation is to place into the left hand end of the barrel a washer cup *y* containing the felt washer *z*. The end plate 1 is then placed over the lugs 2 on the left hand end of the barrel and these lugs are turned over in practically the same way as the lugs at the other end of the barrel. It will be seen that the points *c* stop the washer cup *y* from traveling further inward, while the end plate 1 stops the cup from traveling outward when the end plate has been locked in place.

Each of the felt washers is notched, as shown in Figs. 4, 5 and 7. So also is the pawl carrier, as shown in Figs. 6 and 8.

These notches form key-way segments adapted to accommodate the lock-seam 3, as shown in Fig. 12, to key these felt washers and the pawl carrier to the barrel. Hence the felt washers and the pawl carrier rotate with the barrel.

The left hand end of the bracket shown in Fig. 15 is provided with a protruding stud 7 which is soldered or in any suitable way pressed into the bracket to become a fixed part thereof. Hence when this stud is inserted in the opening in the felt washer *z* and the bracket secured by screws to the support (the right hand bracket having also been secured by screws to the support), the entire roll assembly is completed.

The details of the manufacturing operations have been rather minutely described because they have a bearing on the design of the structure itself. Many of the elements are given their novel design and arrangement largely in consideration of economical and expeditious manufacturing methods.

It is also to be noted that in this assembly the pawl carrier carries only a single pawl and is located at the extreme right of the barrel. By using a single pawl only one pawl is in the pawl carrier and this is always caught. Where two pawls are used one pawl is always free and vibrating up and down, making an objectionable noise. Also when a pawl carrier of this type is located at the center of the barrel, as it has been in some previous patent disclosures, the pawl carrier is in a position where it is subjected to the maximum vibration.

What I claim is:

1. In a curtain roll, the combination of a barrel, a rod supported in said barrel and provided with a pawl recess, a pawl carrier keyed to the barrel and mounted to rotate about the rod and provided with a pawl arranged to engage the pawl recess and also having an extended hub, and a coiled spring having a press fit over the hub at one end and a press fit over the rod at the other end to anchor the spring to the barrel and to the rod.

2. In a curtain roll, the combination of a barrel, a rod upon which the barrel is mounted to rotate, said rod being provided with a pawl recess, a pawl carrier provided with a pawl adapted to engage said recess and having an extended hub, and a spring secured at one end to the rod and secured at its opposite end to the hub by having a press fit over said hub.

3. In a curtain roll, the combination of a barrel, a rod upon which the barrel is mounted to rotate, and a torsion spring coiled about the rod and having one end connected with the barrel to rotate therewith and having the other end provided with a press fit over the rod.

4. In a curtain roll, the combination of a barrel provided with one or more projections pressed therein near one end, a rod provided with a pawl recess and arranged to have a definite position with respect to the end of the barrel, and a pawl carrier provided with a pawl, said pawl carrier adapted to engage about the rod and be located in proper proximity to the pawl recess by reason of en-
gaging against said projection or projections pressed in the barrel.
5. In a curtain roll, a major sub-assembly comprising a rod provided with a shoulder on its outside end, a bearing member in-
tended to rotate on the rod and threaded on the rod inside of said shoulder, a spring se-
cured to the member at one end and at the other end secured to the rod, a second bearing member at the inner end of the spring arranged to rotate on the rod, and means on the inner end of the rod for holding the first and second bearing members and the spring from disengaging from the inner end of the rod.
6. In a curtain roll, a major sub-assembly comprising a rod provided with a shoulder on its outer end, a bearing member retained on the inside of said shoulder and arranged to rotate on the rod, a spring secured at its outer end to said bearing member and se-
cured at its inner end to the rod, a second bearing member at the inner end of the spring, and keys upset on the end of the rod for holding the two bearing members and the spring from sliding off the inner end of the rod.
7. In a curtain roll, a major sub-assembly comprising a curtain rod provided with a shoulder at its outer end, a felt washer en-
gaging the inside of a said shoulder, a pawl carrier or bearing member engaging on the rod to the inside of the felt washer, a spring engaging about the rod and having its outer end secured to the pawl carrier, a felt washer secured on the rod at the inner end of the spring, and means on the inner end of the rod for holding the parts assembled on the said rod.
8. In a curtain roll, a major sub-assembly comprising a rod having a shoulder on its outer end, a felt washer threaded on the rod to the inside of the shoulder, a pawl carrier or bearing member threaded on the rod on the inside of the felt washer and provided with a relatively long hub portion, a coiled torsional spring having a press fit on said hub portion of the pawl carrier and having its inner end in a press fit on the inner end of the rod, a felt washer threaded on the rod at the inner end of the spring, and means on the inner end of the rod for holding the felt washer and the other parts assembled on the rod.
9. In a curtain roll, a major sub-assembly comprising a curtain rod provided with a pawl recess and a shoulder on its outer end, a felt washer threaded on the rod on the inside of the shoulder, a pawl carrier in the form of a metal cup provided with a hub portion threaded on the rod on the inside of the felt washer and serving as a bearing member, said pawl carrier also provided with a pawl adapted to engage the pawl recess in the rod, a torsional spring engaging about the rod and the hub of the pawl carrier and secured to the latter, a felt washer threaded on the rod at the inner end of the spring, and means on the inner end of the rod for preventing the second felt washer and the other parts coming off the rod.
10. In a curtain roll, the combination of a barrel, a rod upon which the barrel is mounted to rotate and provided with a pawl recess, a pawl carrier and pawl keyed to the barrel, the said rod provided with a shoulder near its outer end, a cap plate threaded on the rod and adapted to engage the outside of the shoulder, said cap plate being secured to the end of the barrel, and a bracket having a tight press fit over the outer end of the rod to hold the rod stationary when the barrel rotates and hold the rod from inward movement with respect to the barrel.
11. In a curtain roll, the combination of a barrel provided with notched ends forming lugs and having one or more projections pressed into the side of the barrel near such end, a rod having a shoulder at its outer end, one or more bearing members fitted onto said rod at the inside of said shoulder and held by and between the shoulder and the projection or projections in the barrel which act as stops, and a slotted end plate fitted over the lugs on the end of the barrel which lugs are folded down on the outside of the plate, said plate engaging the outside of the shoulder on the end of the rod.
12. In a curtain roll, the combination of a barrel provided with a notched end forming projecting lugs and having one or more projections indented in the side of the barrel to act as stops, a rod provided with a shoulder at its outer end having a pawl recess cut in the rod to the inside of the shoulder, a pawl carrier including a metal cup threaded on said rod and engaged against the outside of the projection or projections in the sides of the barrel, the inside of the shoulder serving to retain the pawl carrier from sliding outwardly on the rod, and a slotted plate adapted to fit over the lugs on the end of the barrel and threaded to the outside of said shoulder on the rod, the said lugs being folded over to retain the plate in place.

In testimony whereof I affix my signature.
ERNEST E. HEINTZ.
